Attorney

UNITED STATES PATENT OFFICE.

PORTER B. HAND, OF HANDSBOROUGH, MISSISSIPPI.

SAD-IRON.

SPECIFICATION forming part of Letters Patent No. 437,758, dated October 7, 1890.

Application filed March 10, 1890. Serial No. 343,438. (No model.)

To all whom it may concern:

Be it known that I, PORTER BRISTOL HAND, a citizen of the United States, residing at Handsborough, in the county of Harrison and State of Mississippi, have invented certain new and useful Improvements in Sad-Irons; and I do declare the following to be a full, clear, and exact description of the invention, such as will enable others skilled in the art to 5 which it appertains to make and use the same.

My invention relates to an improvement in sad-irons, and the novelty will be fully understood from the following description and claim, when taken in connection with the annexed 10 drawings, in which—

Figure 1 is a side view of the iron with the handle in position. Fig. 2 is an interior view of the arm attached to the iron, showing the opening and pin. Fig. 3 is a view of the top 15 of the arm. Fig. 4 is an end view showing the shield attached to the handle. Fig. 5 is a side view of the handle, showing the bolts and shield in position. Fig. 6 is a side view of the key. Fig. 7 is a top view of the shield 20 with one end of the same curved.

Similar letters refer to similar parts throughout the several views.

Referring to the drawings annexed, A represents an iron; B, the arms rigidly attached 25 to the iron, and which have an opening I therein, as shown in Figs. 2 and 3.

H designates a pin or cross-piece, as shown in Fig. 3.

D designates hook-bolts, which are attached 30 to handle C, one of said bolts being rigidly attached and the other extending within the handle and resting upon a spring, as shown by L in Fig. 5.

E is a shield made, preferably, of metal 35 with openings a in the same for attaching a pad or covering F, which may be of leather or other material, the ends of shield E being provided at intermediate points with two slots P, which when the ends are bent inwardly 40 upon themselves are easily adjusted on the

hook-bolts D, as shown in Fig. 1, G being a key which prevents the slotted ends of the shield E from being released from the hook-bolts D, the key passing through slots in the bolts and also through the loops at the ends 50 of the shield.

K are slots, within which the pins or cross-pieces H rest when handle C is in position, as shown in Fig. 1.

The mode of operation is as follows: The 55 handle C being detached, as shown in Fig. 5, the rigid hook-bolt D is inserted in the opening I and the slot K engages the pin or cross-piece H, and by pressing back the spring hook-bolt D on the opposite end of handle C by 60 means of pressure exerted on the slotted end of shield E the pin or cross-piece H may be placed within the slot K and a positive fastening be made, as shown in Fig. 1. When it is desired to detach the handle C, simply press 65 back the spring hook-bolt D and the pin or cross-piece H is released from the slot K, and the handle may be readily removed from arms B of the iron.

In heating the irons the handles are detached, and as each iron is desired to be used the handle is attached in the manner described. One handle can be used for several irons.

Having described my invention, what I 75 claim, and desire to secure by Letters Patent, is—

The combination of the detachable handle provided with bolts, the shield having its opposite ends bent or looped and slotted, and 80 the key adapted to enter the slots of the bolts and also the loops of the shield, substantially as specified.

In testimony whereof I affix my signature in presence of two witnesses.

PORTER B. HAND.
